INVENTOR

Herbert C. Grannis
 By Frank W. Hoerner,
 ATTORNEY.

UNITED STATES PATENT OFFICE.

HERBERT C. GRANNIS, OF INDIANAPOLIS, INDIANA, ASSIGNOR TO BRIANT SPECIALTY COMPANY, OF INDIANAPOLIS, INDIANA, A CORPORATION.

BALL-DISPENSING DEVICE FOR GAME APPARATUS.

1,395,705.

Specification of Letters Patent.

Patented Nov. 1, 1921.

Application filed August 26, 1918, Serial No. 251,475. Renewed June 27, 1921. Serial No. 480,908.

To all whom it may concern:

Be it known that I, HERBERT C. GRANNIS, a citizen of the United States, residing at Indianapolis, in the county of Marion and State of Indiana, have invented certain new and useful Improvements in Ball-Dispensing Devices for Game Apparatus, of which the following is a specification.

This invention relates to certain means used in connection with that class of game apparatuses employing an alley upon which balls are rolled; and one of the objects of the invention consists in the provision of certain means by which a uniform determined number of accumulated spent balls can be delivered to each player in successive order, thereby saving much time that would otherwise be lost in counting the balls, besides depriving one player of the opportunity of surreptitiously taking advantage of another by the addition of an excess number of balls above the prescribed allotment.

A further object of the invention consists in the provision of certain means whereby the customary number of balls allotted each player can be reduced, thereby not only shortening the length of time to play the game, but allowing a greater number of games to be played within a certain period of time with a corresponding increase in the earning capacity of the apparatus when the game is operated for profit.

A still further object of the invention consists in the provision of certain means of the above character which is simple in construction, efficient in operation and economical to manufacture.

I accomplish the above objects of the invention, and such others as may appear from a perusal of the specification and claims, by means of the construction illustrated in the accompanying drawings, forming a part hereof, in which—

Figure 1 is a perspective view of a conventional style of a game apparatus showing the location of my invention therein. Fig. 2 is a fragmentary detail top or plan view of the ball dispensing mechanism embodying my invention. Fig. 3 is a longitudinal vertical sectional view, on the line 3—3 in Fig. 2. Fig. 4 is a transverse sectional view of the ball return race-way, showing my improved ball dispensing mechanism in operative position. Fig. 5 is a fragmentary detail plan view of the tripping device.

Referring to the drawings, 10 represents the floor of the alley upon which suitable balls 11 are rolled, and said alley terminates in a semi-circularly formed deflecting member 12 for guiding the balls 11 upwardly and into a ball receiving trough 13. The balls are discharged from one end of the trough 13 into a hopper 14 from which they pass into an inclined ball return chute or race-way 15 to the players' end of the alley. As the spent balls accumulate *seriatim* in the depressed end of race-way 15 by arresting their movement through the medium of a stationary stop 16, the number of balls ordinarily delivered to a player at one time rest upon a hinged supporting floor 20 which is suitably hinged to one of the side walls of chute 15, by means of the hinges 21. The upper surface of hinged supporting floor 20 is arranged substantially in the same plane as the upper surface of the stationary floor 22 of chute 15, as clearly shown in Fig. 3 of the drawing. Hinged supporting floor 20 is normally held in its elevated position, so as to support the incoming spent balls 11, by means of a rocker-arm 25 which is pivoted midway its length, as at 26, in the side wall of chute 15. Rocker-arm 25 is actuated by means of a shifting-rod 27 which is pivotally connected to a hand lever 28. When a player takes his turn at play he actuates hand lever 28 so as to move rocker-arm 25 from the position shown in full lines to the position shown in dotted lines in Fig. 5, whereby said rocker-arm is moved from beneath hinged supporting floor 20, allowing the latter to move downwardly into a vertical position as shown by means of the dotted lines in Fig. 4. As the length of hinged supporting floor 20 is equal to the combined diameters of ten of the balls 11, this being the number of balls ordinarily allotted to each player, the above number of balls will be simultaneously discharged by gravity from chute 15 into a ball receiving receptacle 30 where they become available to the player. To prevent a greater number than the allotted number of balls to be discharged from chute 15 into receiving receptacle 30 when hinged supporting floor 20 is actuated, I provide a stop-means which is carried by said floor 20

and which is lowered into position as floor 20 is depressed and thereby temporarily blocks further movement of the accumulated balls remaining in chute 15 and back of the 5 hinged floor 20. The above stop-means comprises a blade 32 which is secured to the end of hinged floor 20 furthermost from the players' end of the alley and blade 32 is lowered into position, as shown by means 10 of the dotted lines in Fig. 4, when hinged floor 20 is depressed so as to insure the discharge of the desired number of balls from chute 15 into the ball receiving receptacle 30. After the allotted number of balls has 15 been discharged from chute 15, the player releases hand-lever 28 and the latter is returned to normal through the medium of a spring 29. As hand-lever 28 returns to normal position, it moves shifting-rod 27 longitudinally and oscillates rocker-arm 25 on its pivot to cause the curved end of the latter to contact and return movable floor 20 to normal for receiving the incoming balls 20 freed by the removal of blade 32.

25 When it is desired to reduce the number of balls ordinarily allotted to each player, the same may be accomplished by means of temporary stops 35 which can be transversely arranged in chute 15 and in the 30 channels 36 which are cut in the inner surfaces of the side walls of chute 15. As shown, one of the temporary stops 35 may be arranged within chute 15 a sufficient distance from stationary stop 16 to eliminate 35 two of the balls from the usual allotment, or the distance between temporary stop 35 and stationary stop 16 can be increased so as to eliminate four of the allotted number of balls to a player. By this arrangement the 40 operator is enabled to shorten the length of the games, and rendering the apparatus available to an increased number of players within a given period of time.

When the game apparatus is operated for

profit, it is desirable that payment shall be 45 made by the player when receiving his allotment of balls, and it is furthermore desirable to collect the money paid by suitable automatic means, so as to relieve the operator from constant attendance at the apparatus. To accomplish the above object I provide suitable coin actuated mechanism which is arranged within a casing 40 having a coin receiving opening 41 in its top, the coin actuated mechanism being connected to 50 and actuated by a hand-lever 28 when the several parts are released through the introduction of a coin for the discharge of each allotment of balls.

Having thus fully described my said invention, what I desire to secure by Letters Patent, is—

1. The combination with a game apparatus including an alley for rolling balls, of a ball return raceway comprising a fixed 65 ball supporting floor and a movable floor, means for hingedly mounting the movable floor, means for supporting said hinged floor in normal horizontal position, and means for actuating said supporting means for releasing and for positively returning the movable floor to normal position.

2. The combination with a game apparatus including an alley for rolling balls, of a ball return raceway comprising a fixed 75 and a movable section, means for actuating said movable section for freeing the balls from the latter by gravity, a stationary means for starting the column of accumulated spent balls at a determined point, and 80 removable means for varying the number of balls usually allotted to each player.

In witness whereof, I have hereunto set my hand and seal at Indianapolis, Indiana, this 22d day of August, A. D. one thousand 85 nine hundred and eighteen.

HERBERT C. GRANNIS. [L.S.]
